CLAIM

The ornamental design for an automobile fuel door scratch guard, as shown and described.

DESCRIPTION

FIG. 1 is a front elevation view of an automobile fuel door scratch guard showing our new design, the back view being flat and unornamented;

FIG. 2 is a left-side elevation view thereof;

FIG. 3 is a right-side elevation view thereof;

FIG. 4 is a bottom plan view thereof;

FIG. 5 is a front elevation view of an automobile fuel door scratch guard showing a second embodiment of our new design, the back view being flat and unornamented;

FIG. 6 is a left-side elevation view of FIG. 5;

FIG. 7 is a right-side elevation view of FIG. 5; and

FIG. 8 is a bottom plan view of FIG. 5.
